UNITED STATES PATENT OFFICE.

EDWARD P. FUHRMANN, OF DES MOINES, IOWA.

TIE AND TIE PLATE.

Application filed October 1, 1924. Serial No. 741,040.

To all whom it may concern:

Be it known that I, EDWARD P. FUHRMANN, a citizen of the United States, and a resident of Des Moines, in the county of 5 Polk and State of Iowa, have invented a certain new and useful Tie and Tie Plate, of which the following is a specification.

The purpose of my invention is to provide a tie and tie plate of simple construction. 10 A further object is to provide such a tie and tie plate construction of unusual durability.

Another purpose is to provide such a construction having the parts so arranged as 15 to afford maximum protection against the spreading of railroad rails used therewith.

Still another object of my invention is to provide such a construction having a tie plate so constructed and arranged that it 20 may be readily and easily removed for purposes of replacement and which when in use will prevent tilting as well as spreading of the rails in an efficient manner.

With these and other objects in view, my 25 invention consists in the construction, arrangement and combination of the various parts of my tie and tie plate, whereby the objects contemplated are attained, as hereinafter more fully set forth, pointed out in 30 my claims, and illustrated in the accompanying drawings, in which:—

Figure 1 shows a top or plan view of a section of railroad track equipped with a tie and tie plate construction embodying my invention.

Figure 2 shows a side elevation of my tie and tie plate construction.

Figure 3 is a detailed, sectional view taken on the line 3—3 of Figure 2.

Figure 4 is a side elevation of a tie, partly in section, showing my tie plate construction in section, taken on the line 4—4 of Figure 3.

Figure 5 is a perspective view of the blank from which the tie plate is formed; and

Figure 6 is a perspective view of the lug used on the tie plate.

In the accompanying drawings, I have used the reference character 10 to indicate generally the tie forming in combination a 50 part of my invention. This is preferably of the H-beam type, but in any event should have at its upper portion laterally projecting flanges.

The rails 11 are held on the tie 10 by a 55 tie plate which forms part of my invention.

In Figure 5, I have shown a blank from

which my improved tie plate may be formed. This comprises a central, flat body portion or plate 12, which has at one side a projecting tongue 13, which in the completed 60 form is folded over above the body 12 to form a channel-shaped member to receive one side of the base of the rail, as shown for instance in Figure 4.

What I shall call the ends of the tie plate 65 portions of the body 12 are folded or bent over as indicated at 14 in Figure 3 to form with and below the body 12 channels for receiving the flanges at the upper part of the tie 10.

The body of the plate 12 has near its side opposite the tongue 13 a plurality of holes 15 to receive bolts 16 hereinafter again referred to.

The same side plate is formed with a backing or stop member 17 rigidly connected with the body of the plate. The stop member 17 may be formed from the tongue bent over the body of the plate and preferably riveted thereto as at 18.

With the plate, I provide a locking lug 19, shown in Figure 6, which preferably has a flat upper surface, a flat lower surface 19^a for a portion of its width and a beveled lower surface portion 19^b adapted to overlie 85 the base of the rail on the side opposite from the tongue 13.

In the actual use of my improved tie and tie plate construction, the ties are placed in the ordinary way. The tie plates are 90 then slid on the ties from the ends with the channels formed by the members 14 receiving the flanges at the upper part of the tie.

The rails are placed in position with the tongue 13 overlying the flange as shown 95 in Figure 4, and the plate and rail are then moved to position where the holes 15 register with holes 20 in the flanges of the ties.

The locking lug 19 is then placed in position partially overlying the opposite side of the base flange of the rail and with its flat under surface portion 19^a resting on the plate 12.

The bolts 16 are inserted through the 100 holes 20 and 15 and through registering holes 21 in the lug 19. Washers 22 and nuts 23 are then placed on the bolts. The lug is backed against lateral movement away from the rail by the backing member 17.

A tie and tie plate structure of the kind herein described has a number of important

advantages, some of which will now be referred to.

It will be noted that the ties may be made of proper metal, so that they will have a very long life and need to be replaced only at rare intervals.

A tie plate of the kind herein shown always holds the rails rigidly in place on the ties. The rail is held against spreading or 10 tilting in an extremely efficient way. It is to be noted that rails ordinarily spread, not by sliding horizontally, but by tilting and sliding.

Frequently they slide because the spikes 15 on the inside of the rail become loose and the rail is then allowed to tilt laterally.

With my improved tie and rail plate construction, the rail is prevented from spreading by means of the member 13 and 20 the plate 12 and the fastening bolts 16. The tilting, which usually occurs when the rails spread, is prevented by the member 13, by the locking lug 19 and the bolts 20, and is also prevented by the construction of the 25 members 14 forming the channels receiving the flanges at the upper part of the ties, which coact with the bolts 16 in holding the rail in place. These channels also take much of the strain off the bolts 20.

30 It will be noted that when there is a tendency of the rail to tilt to the left from its position shown in Figure 4, the channels

formed by the members 14 will hold the tie plate against tilting. This makes it possible for the member 13 to resist such tilting movement.

If it should be desired to replace the rail plates, the bolts 16 and lugs 19 are removed, whereupon the plates can be slid laterally until the rail can be lifted clear of the member 13 and the member 17. The plate may then be slid to the end of the tie and removed therefrom and another plate slid on and assembled in position with relation to the tie and brace.

I claim as my invention:—

In a structure of the class described, the combination of a tie having opposite flanges at its top, and a rail with a metal tie plate having at its ends portions bent around the edges of the flanges of the tie for locking the plate to the tie against tilting or vertical movement and having at one side a portion bent to form a channel receiving one side of the rail base and at the opposite side a portion bent over the body of the plate and fastened thereto, a locking lug resting on the plate between said last portion and the rail and overlying the rail base, and bolts spaced lengthwise of the track extended through 60 the lug, the plate and the tie flanges.

Des Moines, Iowa, September 20, 1924.

EDWARD P. FUHRMANN.
